AEROPLANE STRUCTURE

Filed July 11, 1923

UNITED STATES PATENT OFFICE.

PAUL G. ZIMMERMANN, OF KEYPORT, NEW JERSEY, ASSIGNOR TO AEROMARINE PLANE & MOTOR COMPANY, OF NEW YORK, N. Y., A CORPORATION OF NEW YORK.

AEROPLANE STRUCTURE.

Application filed July 11, 1923. Serial No. 650,768.

To all whom it may concern:

Be it known that I, PAUL G. ZIMMERMANN, a citizen of the United States, and a resident of Keyport, in the county of Monmouth and 5 State of New Jersey, have invented a new and useful Aeroplane Structure, of which the following is a specification.

The invention relates to metal aeroplane or flying-boat construction, and particularly to 10 surfaces, such as, specifically, the elevator and the vertical and horizontal stabilizers of the tail. The object is to secure a high degree of lightness and strength for such parts, with facility of manufacture; and 15 this is accomplished by means of certain elements and forms combined for special advantage in a type of construction novel in the art.

In the accompanying drawings, forming 20 part hereof, the invention is illustrated as an elevator frame; and in the said drawings:

Fig. 1 is a plan view;

Fig. 2 is a sectional view on the line 2—2 of Fig. 1;

Fig. 3 is a sectional view on the line 3—3 of Fig. 1;

Fig. 4 is a sectional view on the line 4—4 of Fig. 1; and

Fig. 5 is a sectional view on the line 5—5 of Fig. 1.

The elevator frame selected for illustration has a hollow main member consisting of a straight tube 2, forming the leading edge. Eye-bolts 3 inserted through this tube 35 at intervals afford means for hinging the elevator to the trailing edge of the horizontal stabilizer (not shown).

The trailing edges, outer and inner, of the elevator frame are formed of small tubes 4, 40 5. The tubes 4 change from a round section to a flattened elliptical section between the points *x* and *y*.

Interiorly the frame is comprised of light ribs, consisting of fore and aft members 6,

transverse members 7, and diagonal members 8. The members 6 are continuous and the members 7 and 8 are spliced at the junctions, which consist of pairs of small spaced, plane plates 9 applied at opposite sides of the frame to surfaces of the ribs.

The ribs are constructed of thin material made into flat angular sections, comprising web walls 10, depthwise of the frame, and face walls 11 lying in spaced planes and having the plates 9 riveted to them. An open-sided box rib consisting of a wall 10 and two walls 11 extending in one direction therefrom, and bent again at the edges, forming lips 12, is of especial advantage. The ribs decrease in depth from the 60 main edge member 2 to the minor edge members 4, 5, this being accomplished by tapering the webs 10 so that the face walls 11 converge, and the tapering in the several parts is so related that the face walls of the 65 members meeting at a junction are flush with each other at opposite sides, that is to say at top and bottom, so that the plates 9 lie flat upon the meeting walls, to which they are riveted.

Other riveted junction plates 13 and 14 unite the ribs with the members 2, 4 and 5.

Various forms of the invention will suggest themselves to those skilled in the art.

What I claim as new is:

In aeroplane construction, a metal elevator or like frame comprising major and minor edge members, and a system of intersecting ribs of thin material formed into web and face walls, with pairs of plane, spaced junction plates embracing the joints and united at opposite sides to said face walls, the ribs decreasing in depth from the major to the minor edge members in such manner that the face walls of the rib members meeting at the 80 several junctions are flush with each other forming flat seats for the plates.

PAUL G. ZIMMERMANN.
